UNITED STATES PATENT OFFICE

HOWARD SHONDELL, OF FORT WAYNE, INDIANA, ASSIGNOR TO GENERAL CABLE CORPORATION, OF NEW YORK, N. Y., A CORPORATION OF NEW JERSEY

WINDING MACHINE

Application filed April 25, 1931. Serial No. 532,760.

This invention relates to coil winding machines of the multiple coil type wherein a plurality of separate coils of wire are wound on a core and the paper insertions between the wire layers are formed by winding a sheet of paper about the entire "stick" of coils after each layer is wound. In machines of this type, a gang of knives is arranged for movement toward and from the spindle for cutting the paper insertions between the separate coils. A cutter guard is usually provided for shielding the knives when in non-cutting position to prevent possible injury to the operator, but as heretofore constructed, such guards have not been entirely adequate.

An object of this invention is to provide an improved cutter guard for machines of the type set forth constructed and arranged to provide an operator with protection against accidental injury.

A further object is to provide a cutter guard for coil winding machines having an improved construction arranged to be held against displacement when the cutters are inoperative.

These and other objects which will be apparent to those skilled in this particular art are accomplished by means of the invention illustrated in the accompanying drawings in which,

Fig. 1 is a perspective view of part of a coil winding machine provided with a cutter guard constructed and arranged in accordance with one embodiment of this invention.

Fig. 2 is a transverse sectional view through the machine shown in Fig. 1 illustrating one position of the parts, and

Fig. 3 is a similar view showing the parts in a different position.

The illustrated embodiment of the present invention includes a frame which is associated with the gang of knives so as to cover the knife blades when the latter are in non-cutting position and to be moved to uncover the blades when they are shifted toward the winding spindle to cut the sheet material between the different coils. Means is provided for holding the guard against displacement

when the cutters are inoperative and the guard in cutter covering position.

The invention is illustrated in connection with a winding machine having the usual coil winding spindle 5 which may be driven by a suitable motor 6 for winding a plurality of separate coils 7 of wire 8 delivered to the machine from the usual supply spools (not shown). After each layer of wire is wound, an insulating layer of suitable sheet material 9 received from a roll 10 is fed to the spindle 5 and wound thereon, the single sheet being of sufficient width to extend the entire length of the stick of coils being wound on the machine. The sheet material is severed between the separate coils by a gang of knives which are movable into and out of cutting position. The knives include a plurality of blade holders 11 provided with cutting blades 12 and secured to a cutter supporting shaft 70 13 mounted in supporting arms 14 which are pivotally secured to spaced upright frame members 15 of the machine. One of the cutter supporting arms is provided with an operating handle 16 by means of which the cutters are swung toward and from the spindle into and out of sheet cutting position.

In order to cover the blades 12 when in non-cutting position so as to protect the operator against accidental injury, a U-shaped cutter guard 17 is pivotally mounted on the cutter rod 13 for swinging movement thereon and one arm 17 of the guard is extended above the supporting rod and connected by a link 18 to a curved guard actuator 19 having an arcuate slot 20 receiving supporting bolts 21 by means of which the actuator is movably supported upon the adjacent arm 14. The lower angularly extending leg 22 of the actuator 19 engages the face of one of the uprights 15. A spring 23 connects the upper portion of the extended guard arm 17 with the upper part of the actuator 19. The cutters and associated parts are normally held in non-cutting position by a weight 24 mounted on supporting arm 25 pivotally secured to an ear 26 on the top face of the operating arm 14.

During normal operation of the winding machine, the weight 24 and spring 23 hold the

- parts in non-cutting position illustrated in Fig. 2, and it will be apparent that the guard 17 is held against accidental movement on the part of the operator, by the actuator 19 and link 18, which obviously prevent movement of the guard 17, the angular position of the link 18 with relation to the arcuate slot 20 and hinge 21 being such that swinging movement of the guard 17 on the supporting rod 13 is resisted. When it is desired to sever the sheet material between the coils, the cutters 12 are moved downwardly into cutting position, as shown in full lines in Fig. 3, by downward movement of the handle 16, which causes the cutter supporting arms 14 to swing downwardly around the supporting pivots, the supporting pins 21 moving through the arcuate slot in the guard actuator 19 to the position shown, the actuator being held against swinging movement by engagement of the leg 22 with the front face of the frame member 15, the actuator merely sliding downwardly along such face. The relative movement of the actuator and the arm 14 thus causes the link 18 to swing the guard 17 and uncover the blades 12 so that they can be moved into cutting engagement with the sheet material. Upon completion of the cutting operation, the arms 14 are returned to the position shown in Fig. 2, the actuator 19 rides upwardly along the face of the frame member 15 and the spring 23 which has been tensioned by movement into the cutting position shown in Fig. 3, holds the actuator 19 in operative position and causes the guard 17 to return to the position illustrated in Fig. 2.
- The cutters and associated parts can be raised into the extreme upper position to give the operator access to the spindle 5 by lifting the handle 16 and moving the parts into the position shown in dotted lines in Fig. 3. In this position also the leg 22 of the cutter 19 remains in engagement with the frame member 15 and continues to maintain the guard 17 in protecting position over the blades 12. Although I have described a specific embodiment of this invention in detail, it will be apparent that various changes and modifications can be made therein without departing from the spirit of the invention or the scope of the appended claims.
- I claim as my invention:—
1. The combination in a winding machine of a winding spindle, means for winding sheet material thereon, cutters movable toward and away from said spindle for severing said material, a guard for shielding said cutters and means for moving said guard to uncover said cutters when said cutters are moved toward said spindle.
  2. The combination in a winding machine of a winding spindle, means for winding sheet material thereon, cutters movable toward and away from said spindle for severing

said material, a movably mounted guard for shielding said cutters when in non-cutting position and means for holding said guard against movement when said cutters are inoperative. 70

3. The combination in a winding machine of a winding spindle, means for winding sheet material thereon, cutters movable toward and away from said spindle for severing said material, a movably mounted guard for shielding said cutters when in non-cutting position, means for holding said guard against movement when said cutters are inoperative, and means for moving said guard to uncover said cutters when said cutters are moved into cutting position. 75 80

4. The combination in a winding machine of a winding spindle, means for winding sheet material thereon, a cutter bar, one or more cutters supported thereon, a movable support for said bar for moving said bar toward and away from said spindle to shift said cutters into and out of cutting position, a guard for covering said cutters when in non-cutting position and means for holding said guard against movement when said cutters are in non-cutting position. 85 90

5. The combination in a winding machine of a winding spindle adapted to wind sheet material thereon, a cutter bar having a plurality of cutter blades secured thereto and movable into and out of sheet cutting position, a pivotally mounted support for said bar, a cutter guard supported thereby so as to cover said blades when in non-cutting position, means mounted on said movable support and connected to said guard for movably holding said guard against movement and operative for shifting said guard to uncover said blades when moved into cutting position. 95 100 105

6. The combination in a winding machine of a winding spindle adapted to wind sheet material thereon, a cutter bar having a plurality of cutter blades secured thereto and movable into and out of sheet cutting position, a pivotally mounted support for said bar, a U-shaped cutter guard pivotally supported thereby so as to normally cover said blades, an actuator movable with said support and means connecting said actuator to said guard so as to move said guard to uncover said blades when said blades are moved into cutting position and to hold said guard against movement in normal blade covering position. 110 115 120

In testimony whereof, I have signed my name to this specification this 22d day of April, 1931.

HOWARD SHONDELL.
